UNITED STATES PATENT OFFICE.

GEORGE C. RUSSELL, OF POUGHKEEPSIE, NEW YORK.

HORSESHOE-BLANK-FORMING MACHINE.

1,266,322.

Specification of Letters Patent. Patented May 14, 1918.

Application filed May 4, 1917. Serial No. 166,408.

To all whom it may concern:

Be it known that I, GEORGE C. RUSSELL, a citizen of the United States, residing at Poughkeepsie, in the county of Dutchess and State of New York, have invented new and useful Improvements in Horseshoe-Blank-Forming Machines, of which the following is a specification.

My invention relates to a horse shoe blank forming machine and has for its primary object to shape a billet into the form required for making horse shoes, a feeding means being embodied therein whereby the operator may feed a heated billet to the machine at any time during its cycle of operations.

Another object of my invention is to provide a horse shoe blank forming machine which first bends the billet into the shape required and then flattens the same to remove all inequalities of the blank which result from the forming operation.

With these and other objects in view which will be hereinafter fully described and particularly pointed out in the claims, the invention consists in the novel construction and arrangement of parts illustrated in the accompanying drawings forming a part of this specification, in which:—

30 Figure 1 is a side elevation of a horse shoe blank forming machine embodying my invention,

Fig. 2 is a top plan view of the bending mechanism,

35 Fig. 3 is a top plan view of the flattening mechanism of the device,

Fig. 4 is a partial sectional side elevation of the bending mechanism showing the parts in a different position from that designated in Figs. 1 and 2,

40 Fig. 5 is a partial sectional side elevation of the flattening mechanism showing the parts in a different position from that designated in Figs. 1 and 3.

45 Fig. 6 is a perspective view of the die block and the horse shoe thereon with means for removing the shoe therefrom.

Fig. 7 is a sectional detail view of the former with its associated parts.

50 Fig. 8 is a detail view showing the end of the former.

Fig. 9 is a cross sectional view showing the sliding table for carrying the blanks to the flattening mechanism.

In the drawings 1 designates generally a frame upon which the forming mechanism of the device is mounted. At one end of the frame a transverse shaft 2 is journaled, and a former cam 3 is mounted on said shaft at a point intermediate the ends thereof. A guideway 4 is mounted on the frame 1 and extends forwardly from the shaft 2 in line with the former cam 3, and a former carriage 5 is mounted in said guides for sliding movement and has its rear end abutting the cam 3. A pulley 6 is mounted upon an extension 7 at the rear end of the frame 1, and a flexible cable 8 has its one end secured to an eye bolt 9, which is mounted on the carriage 5, and is trained over said pulley 6, and has a weight 10 secured on the other end thereof whereby said carriage is held in engagement with the cam 3.

The former carriage 5 extends in front of the guides 4 and has a forming block 11 mounted at its front end, said former block being shaped to conform with the inclosure of a horse shoe blank. Mounted on the frame 1 is a pair of rollers 12, said rollers being mounted on opposite sides of the forming block 11 and lying in a plane disposed transversely to the path of said former block. Each roller 12 is mounted upon a carriage 13 adapted to move in a transverse guideway 14 formed on the frame 1. A spring 25 is provided for each carriage 13 and serves to normally position the rollers in the path of the forming block 11, stops 16, mounted on the frame 1, serving to prevent said rollers moving too far into the path of the forming block. A billet rest 17 is formed on the frame 1, and is disposed so as to position a billet for proper engagement with the rollers 12 and forming block 11.

A receiving table 18 is mounted on the frame 1 above the mechanism just described, and a pusher plate 19 is mounted for longitudinal movement on the upper surface thereof by means of guideways 20. A guide 21 is mounted on the upper surface of said receiving table 18 on either side of said pusher plate 18, said guides having vertical upwardly distending slots 22 formed therein whereby a billet may be properly placed upon said receiving table by the attendant. The guides 21 are adjustable to accommodate billets of different lengths and thicknesses, the lengthwise adjustment thereof be-

2

ing afforded by means of longitudinal slots 23 formed in the base of the guides and clamp screws 24, screw threaded in the receiving table 18 clamping the guides thereon, 5 the adjustment for the width of the billets being afforded by the rear side 25 of each slot being secured to the main portion of the guide by means of a longitudinally slotted extension 26 and a clamp screw 27 engaging said slot and screw threaded into the main portion of the guide. A carrier 28 is mounted for vertical movement in the guide ways 29 mounted upon the frame 1, said carrier 28 having an upwardly extending arm 30 10 disposed on either side of the billet rest 17 at the rear of the rollers 12. A cam 31 is mounted upon the shaft 2 adjacent the cam 3, and a lever 32 is pivoted upon extensions 33 of the frame 1 and has its one end bearing 34 against the cam 31 and has its other end 15 engaging a notch 34 formed in the lower end of the carrier 28. Carrying surfaces 35 are formed upon the upper ends of the arms 30 and have upwardly extending projections 36 upon the rear ends of said surfaces. The cam 31 is adapted to move said surfaces 35 into the plane of the receiving table 18 and to lower the same to the billet rest 17. A second shaft 37 is journaled in the frame 1 20 and extends transversely thereof, and has a crank 38 formed at either end thereof. A gear 39 is mounted on the shaft 2, and a gear 40, equal in size to the gear 39, is mounted upon the shaft 37 and meshes with 25 said gear 39. A transverse bar 41 is mounted upon the front end of the pusher plate 19, and connecting rods 42 have their front ends pivotally connected to respective ends of transverse bar 41 and have their other ends 30 pivotally connected to respective cranks 38.

In the position of the mechanism as shown in Fig. 1 the pusher plate is just about to engage a billet 33, positioned on the receiving table 18 by the guides 21, to move the 45 billet to the rear end of the receiving table. When the billet reaches the end of the receiving table the carrying surfaces 35 of the carrier 28 lie in the plane of the receiving table, and upon further movement of the 50 mechanism the pusher plate 19 moves the billet off of the receiving table on to the carrying surfaces 35, the projections 36 serving to prevent the pusher plate moving the billet too far. This position of the mechanism is 55 shown in Fig. 4. Upon further progressive movement of the mechanism the carrier 28 moves downwardly and deposits a billet upon the billet rest 17 at the rear of the rollers 12. The forming block 11 then moves 60 forwardly and the billet is engaged between said forming block and the rollers 12. As the forming block moves forward the billet is bent about said forming block by the rollers 12, the rollers 12 receding, during this 65 movement, against the influence of the

springs 15, as the forming block and the billet pass between said rollers. The forming block then moves the formed billet in front of the rollers 12, and in front of the billet rest where the formed billet drops off 70 of the forming block 11 into a hopper 34.

It will be noted that by the above described feeding mechanism the attendant may place a billet upon the receiving table 18 at any time during the cycle of operation 75 of the mechanism. This is especially advantageous in a machine of this character because the billets must be heated and the attendant cannot always place the billet into the machine at a time respecting the cycle of 80 operation of the machine.

During the bending of the billet by the forming block 11 and the rollers 12 the heel portion of the billet becomes thicker at its edges than it is at its center, due to the displacement of the metal during said bending operation. I provide means for flattening the billet after it has been formed, and during the same heat, as follows. The hopper 34 extends downwardly and has a bottom 45 disposed the thickness of one billet away from the lower end of the hopper, so that, as the billets pile up in the hopper, the lowermost billet may be moved out through the opening between said bottom 45 and the 90 lower end of the hopper 34. A die block 46 is mounted upon a reciprocating table 47 which is mounted in guideways 48 of the frame 1. The surface of said die block 46 is disposed in the plane of the surface 95 of the bottom 45, and said die block is adapted, when in its extreme rear position, to lie adjacent the front end of said bottom 45. A shaft 49 is mounted above said reciprocating table 47 and has a die sector 100 50 mounted thereon, which is adapted to coöperate with the die block 46 to flatten a formed billet therebetween. The shaft 49 is provided with a crank 51 and said crank is connected with the table 47 by 110 means of the adjustable links 52. The die sector 50 and the cranks 51 are so timed that when the table is moving toward the front end of the machine the sector will roll over a formed billet disposed on the 115 die block 46, and when the reciprocating table is moving toward its rear end the sector will not engage the formed billet lying on said die block 46. A lever 53 is pivotally mounted in the frame 1 at a point intermediate the ends thereof, and has its upper end moving in a slot 54 formed in the bottom 45. A slot 55, lying in the plane of the slot 54, is formed in the reciprocating table 47 and the die block 46. A cam 56 is mounted upon 125 the shaft 49, and fulcrumed lever 57, mounted on the frame 1, has its upper end bearing against said cam and has its lower end pivotally connected to the front end of a connecting rod 58, the rear end of said connect- 130

ing rod being pivotally mounted at the lower end of the lever 53. The cam 56 is so timed relative to the reciprocations of the table 47 that when said table is at its extreme rearward position said cam operates the lever 53 through the connecting rod 58, and fulcrumed lever 57, to move a formed billet out from under the pile in the hopper 44 on to the die block 46, whereupon the table 47 moves forwardly under the sector 50 and the formed blank is flattened, as hereinbefore described. It will be noted at this point, that the upper end of the lever 53 has a radially disposed face 59 which engages the edge of a formed blank within the inclosure thereof to move the same out of the hopper, and that said lever 53 has a rearwardly facing cam surface 60 formed thereon so that the lever will raise the pile in the hopper when it moves rearwardly, so that the face 59 may engage the next formed billet preparatory to fitting it upon the die block 46. Upwardly projecting shoulders 46' are formed on the front and rear ends of the die block 46 to retain a formed block thereon in proper position during the reciprocations of the table 47.

A second cam 61 is mounted upon the shaft 49, and a fulcrumed lever 62, mounted on the frame 1, has its upper end bearing against said cam. A bell crank lever 63 is mounted upon a vertical axis in the frame 1. The lower end of the fulcrumed lever 62 is bifurcated, as designated at 64, and the lower arm of said bell crank lever 63 is engaged by the inclosure of said bifurcated end 64. The upper arm of said bell crank lever 63 is offset and extends upwardly from the main portion of the lever. A pusher plunger 65 is mounted in transverse guideways 66 of the frame 1 and has a hole 67 at the outer end thereof loosely engaging the upper arm of the bell crank lever 63.

The main portion of the pusher plunger 65 is disposed in a horizontal plane above a formed blank on the die block 46 and has a rearwardly extending end 65' at its inner end, which is disposed in the horizontal plane of a formed blank on said die block. The cam 61 is so timed relative to the reciprocations of the table 47 that, as the die block 46 is moved toward the rear of the shaft 49, after the same has been flattened as before described, the pusher plunger 65 is operated to engage the blank with the end 65' to push the blank off of the die block 46 into a receptacle 68 at one side of the table 47. After it has been moved inwardly to push a blank off the die block 46 the pusher plunger 65 remains in its extreme inner position, and the table 47 continues to move toward its rearward position where another blank is placed on the die block 46, as designated in Fig. 3, and then moves forward to engage the blank with the die sector

50. During this movement the pusher plunger 65 remains in its extreme inner position with the rearwardly extending end 65' disposed out of the path of the blank. When the blank is moved out of the path of the 70 plunger the cam 61 operates to retract the pusher plunger 65 to its extreme outer position where the end 65' is again positioned out of the path of the blank on the opposite side thereof. The pusher plunger remains 75 at rest in this position until the blank is moved toward the rear of shaft 49 where the plunger is again moved inwardly to push the blank off of the die block 46 as hereinbefore described. 80

Having thus fully described my invention, I claim:—

1. In a device of the character described, the combination with a forming means, of a receiving table, guides adapted to properly position a billet on said receiving table, a carrier adapted to receive a billet from said receiving table and to convey the same to a position for engagement by said forming means, a pusher plate adapted to engage a 90 billet positioned on said receiving table by said guides and to move the same on to said carrier, and means for actuating said pusher plate, said carrier, and said forming means sequentially. 95

2. In a device of the character described, the combination with a receiving table, guides adapted to properly position the billet thereon, a vertically movable carrier, a horizontally movable pusher plate for pushing the billet from the table on to said carrier, and a horizontally movable forming means to which the carrier delivers the billet. 100

3. In a device of the character described, the combination with a receiving table, guides adapted to properly position the billet thereon, a carrier, a pusher plate for pushing the billet from the table on to said carrier, a billet rest for receiving the billet from the carrier, forming means receiving the billet from said rest, and means for actuating said parts. 105

4. In a device of the character described the combination with a receiving table, guides adapted to properly position the billet thereon, a carrier, a pusher plate for delivering the billet to the carrier from the table, a billet rest receiving the billet from the carrier, a pair of spaced rollers located in front of said billet rest, and a forming 120 block for moving the billet from the rest and between the rollers. 115

5. In a device of the character described, the combination with a pair of rollers, of a forming block adapted to move therebetween, a carrier adapted to convey a billet to a position for engagement by said forming block and rollers, said forming block serving to move the billet out of the path of said carrier and to move the same 130

beyond said rollers, a hopper into which the formed billets fall when moved beyond said rollers, delivering means at the bottom of said hopper for removing the formed billets therefrom one by one, a movable die block adapted to receive the formed billets delivered by said delivering means, a die adapted

means for removing the flattened billet from the die block, and means for actuating said carrier, said forming block, said delivering means, said die, and said removing means sequentially.

In testimony whereof I affix my signature.

GEORGE C. RUSSELL.
